UNITED STATES PATENT OFFICE.

JAMES D. TAGGART, OF DRUMRIGHT, OKLAHOMA.

MINIATURE-BASEBALL GAME-BOARD APPARATUS.

Application filed December 3, 1921. Serial No. 519,614.

To all whom it may concern:

Be it known that I, JAMES D. TAGGART, a citizen of the United States, residing at Drumright, in the county of Creek and State of Oklahoma, have invented certain new and useful Improvements in Miniature-Baseball Game-Board Apparatus, of which the following is a specification, reference being had to the accompanying drawings.

10 It is the purpose of the present invention to provide a game board apparatus for playing miniature baseball indoors, and in such wise as to represent the national game of baseball.

15 Another purpose is to provide an apparatus of this kind, wherein the use of base runners is eliminated, in view of the fact that they would be in the way, while on the board, thereby preventing the players from 20 playing the game to the best advantage, and in the absence of base runners it is the aim to utilize what may be termed as a scorer in combination with the game board apparatus, so as to keep tally of the points 25 of advantage and disadvantage during the progress of the game, hence eliminating the use of such base runners, which would otherwise be knocked off of the board during the playing of the game.

30 Another purpose is that all the points or plays made on this game board apparatus either advances or retards the scoring of each player. Furthermore, there are no plays or points, such as "strike one," or 35 "ball one," etc., as this would merely prolong the game and the game would become monotonous.

40 A further purpose is that the game board apparatus has applied thereon most of the ordinary plays or points that arise in a game of baseball, and these have been arranged on the board, so that each player will make about the same number of put 45 outs and assists and advantages, as may be made by players playing the actual national game on a field.

50 It is obvious that only one player may play the game, and in this case the player usually acts as the umpire, scorer, pitcher, etc., for both sides. However to secure the best results two players should take part in the game.

55 Still a further purpose is the provision of a game board apparatus, in connection with which improved set of rules are used. These rules do not conflict with the rules of the

official game, and are made as brief as possible, yet plain enough that a child may understand them, and before starting the game the rules should be read carefully. 60

Additionally the invention aims to provide a game board apparatus, in connection with which, may be used scoring members, which in the present instance may be termed as balls, three in number, to be used by the 65 opposing players, and which may be pitched upon the game board in order to cover or partly cover any one of the points of advantage or disadvantage, for making up the score of the player. These scoring members 70 or balls are flat and may be smooth, in order to permit them to strike properly on the board and to allow them to slide to some extent when they strike the board, thereby eliminating a certain amount of 75 science in pitching, and in this way giving a player who may be a poor pitcher, about the same chance to win as a good pitcher.

While the design and construction at 80 present illustrated and set forth are deemed preferable, it is obvious that as a result of a reduction of the invention to a more practical form for commercial purposes, the invention may be susceptible of changes 85 and the right to these changes is claimed, provided they are comprehended within the scope of what is claimed.

The invention comprises further features and combination of parts, as will be herein-after set forth, shown in the drawings and 90 claimed.

In the drawings:—

Figure 1 is a plan view of the improved game board apparatus constructed in accordance with the invention, showing the 95 various points of advantage or disadvantage as applied thereon;

Figure 2 is a view of the score card or scorer;

Figure 3 is a plan view of a series of flat 100 scoring or tossing members used in playing the game;

Figure 4 is a view showing a collection 105 of symbols used in representing the points of advantage and disadvantage on the scorer or score card, and also the approximate definitions of the symbols.

Figure 5 is a view showing example 110 number 1 for using the symbols shown in Figure 4 and symbols set forth in the specification; and

Figure 6 is a view showing example num-

ber 2 for using the symbols defined in the specification and those illustrated in Figure 4.

Referring to the drawings, 1 designates a game board apparatus which may be any suitable shape or proportions, and constructed of any suitable material, such as wood, fibre or the like. The game board has printed, lithographed, or otherwise applied thereon an outline of a baseball field 2, which is surrounded by a fence, and also printed, lithographed or otherwise applied on the field is a baseball diamond 4, and 5 designates home plate, 6, 7 and 8 first, second and third bases, while 9 denotes the pitcher's box. While these parts have been so designated, and would lead one to believe the runners were used in moving about over the board, they are merely mentioned, in order to represent a true outline of a baseball field. In playing the game scoring members or what may be termed as balls 10, are used in connection with the game board apparatus. These scoring members or balls are flat and smooth on either face, in fact circular, and their opposite faces have the usual indication of baseball stitches 11, in order to represent a ball.

30

Rules for playing the game.

The game board is placed on any table in a manner, which would permit the different points of advantage and disadvantage to be easily read.

35 The player then steps back a desired distance from the game board, say for instance approximately seven or eight feet, which may be varied according to the desires of the players, then the first player tossing the 40 balls one at a time on the board, the idea being to make the balls light flat upon the board so that they will not roll off. However, if the balls do roll off, or even one or two of them roll off, count the one or those 45 that stop on a play. Then take all three of the balls and pitch them over as before. In fact should the three balls or scoring members roll off pitch all of them over again. In other words keep pitching the balls, until 50 all three light upon the board. It is obvious that should the balls or scoring members which may be furnished with the game become lost, pennies may be used as a very good substitute, or any other suitable flat 55 piece of metal circular in shape.

Considerable care should be taken as to which was the first, the second and the third ball on the board, otherwise it might make a difference in the game. For instance 60 should ball one stop on one base hit, and ball two stop on home run making two scores for the player, and if these balls should be remembered reversely, in fact ball two counted as ball one, and ball one as ball

two, it would give but one score for the player, which would make quite a difference in counting up the score of the game.

The rule for scoring.

The scorer is the opposing player and is also the umpire. Abbreviations should be used in scoring the game such as, if the ball stops on "Out short to first base" the abbreviation should be "S. to 1." "Out third to first base" use 3 to 1. "Fly out center field" 70 use "F. O. C." "Foul out" "Fo. O." "Out second to first base" use 2 to 1. "Out at first base" use "1." "Out catcher to first base" use "C. to 1." "Wild pitch" use "W. P." "Passed ball" use "P. B." "Balk" use "B." 80 "Stolen base" use "S. B." "Out stealing" use "O. S." Error any base or any other player use the letter "E" for error and abbreviate the player's position. For "out hit by batted ball" use "O. H. B." For 85 "ball four" use this sign $\frac{1}{4}$. For "hit by pitcher" use this sign $\frac{1}{4}$. For "one base hit" use this sign $\frac{1}{4}$. For "two base hit" 90 use this sign $\frac{1}{4}$. For "three base hit" use this sign $\frac{1}{4}$. For "home run" use this sign $\frac{1}{4}$.

Example.—The batter gets a "one base" 95 $\frac{1}{4}$. The next batter gets "hit by pitcher" advance the runner on first base to second base this way $\frac{1}{4}$ using the fourth part of a square. Put the batter on first base this 100 way $\frac{1}{4}$. The next batter gets "ball four" $\frac{1}{4}$. Advance both runners already on bases. The runner on second base goes to third base this way $\frac{1}{4}$. The runner on first base goes to second base this way $\frac{1}{4}$. Put the batter on first base this way $\frac{1}{4}$ filling all the bases. We will say the short stop makes an error, use this sign E.S.1. This lets the batter reach first base. All runners on bases advance one base. The runner on third scores, this way $\frac{1}{4}$. The runner on second goes to third base this way $\frac{1}{4}$. The runner on first base goes to second base this way $\frac{1}{4}$. The batter reaches first base this way E.S.1. In advancing a runner always use the fourth part of a square.

Example.—The batter hits a ball to the third baseman, the third baseman makes an error, letting the batter reach first base, use this sign E.3.1. He advances to second base, the pitcher "balking," use this sign E.3.1. He advances to third base on a "passed ball," 125 use this sign E.3.1. He scores on a "wild pitch," use this sign E.3.1.

How to use score card.

When scoring on the card begin at the left hand upper corner of the "score card" going down the card, and always begin on a new inning adjacent where the player left off during the previous inning and write thereon. In cases where the bottom of the "score card" is reached before the player has finished the inning, begin at the top again being careful to mark the scoring in the same inning.

The umpire and his duties.

15 The umpire, who in the present instance is one of the players determines whether or not the ball or scoring member is touching more than the one indication. If the ball or scoring member is touching more than 20 one indication, neither indication shall count. However, the player is entitled to pitch over again, until the ball or scoring member proper stops on only one indication. The ball or scoring member does not have to 25 entirely cover an indication. For instance just so it is touching one of the indications it is all that is necessary. In cases where the ball or scoring member of a player alights on the game board apparatus and 30 overlaps another ball or scoring member, only the ball that touches the indication counts.

Impossible plays.

35 In cases of impossible plays, such as (steal second base) and there is no score on the card indicating that a player has thrown a ball tending to indicate an advance to first base, the pitch of the ball or scoring member would not count. This is called an impossible play. Another impossible play is the act of tossing a ball or scoring member on an indication stating "out stealing home," when the player has just started. 45 To count a score by alighting a ball on an indication upon which this statement is indicated, the player would have to make a previous score by throwing a ball or scoring member on an indication stating advance to third base from home. In other words if 50 there is no score on the card indicating that a supposed runner had made third base, it would be impossible to indicate on the score card any such advance as "out stealing home."

An inning.

Each pitcher shall pitch the balls on the board until three outs are made. When 60 each pitcher has pitched until three outs are made this shall be called an inning. It is obvious that each game consists of nine innings, unless at the end of nine innings the score is a tie. In that event, each pitcher 65 shall keep on pitching as before, until one

side has scored more runs than the other in the same number of innings.

Error.

Certain of the indications on the game board apparatus has "error" thereon, for instance error pitcher, error catcher, error baseman, error short stop, or error fielder, supposedly as dropped ball or batted ball or a thrown ball or as a wild throw, permitting the player to apply a symbol, which constitutes an error, supposedly made by the man in the field, and this gives the player an advanced score on the score card.

Overthrows.

Where a player has thrown a scoring member or ball on the game board alighting it on an indication stating "overthrow," supposedly either by the catcher, the batter has bunted the ball in front of home base, and the catcher has endeavored to put him out at first base, or has thrown wild to another base, or has apparently made a bad throw which apparently the first baseman could not catch, the player indicates a score on the card as though a runner has advanced to second base, advancing the score of the game. All other supposed runners advance two bases.

If a player tosses a ball or scoring member on an indication stating short stop overthrows, a score is applied to the score card indicating advance to second base. In this case all other supposed runners or men advance two bases.

Base hits.

One base hit, two base hit, or three base hit, meaning that the supposed batter has hit a ball from the pitcher, a safe to fair territory, where the basemen or fielders cannot catch, the player is entitled to indicate on the score card a score equal to as many bases, as stated on the indication, for instance three bases, or a home run.

Base hits in cases where a player throws a ball or scoring member on an indication runners on bases, scores, etc., the player indicates on the score card an indication stating that the supposed runner has made one more base than the batter is entitled to.

Home run.

Where a player tosses a ball or scoring member on an indication stating "home run," the player indicates on the score card a symbol to such effect, and in this case all the supposed runners already on bases shall 125 score. In other words when counting up the score, the player counts the number of the score accordingly. In other words when an inning is completed, and the score card states that there are so many supposed run- 130

ners on bases, these runners are counted as having made home plate, therefore a score is read accordingly.

Out strike three.

5 When a player has thrown a ball or scoring member on an indication of the board stating "out strike three," it is supposed that a batter had made three strikes at the 10 ball and missed, therefore failing to advance the score.

Fly out.

When a player throws a ball or scoring 15 member on an indication on which it states a fly out, it means that a supposed ball has been knocked in the air, and thus, therefore the batter is out, and the score first indicating certain supposed runners or men on 20 bases shall not be used to make an advance in the score. In other words the batter is out and no base runner shall be allowed to advance unless the abbreviation (S. A. C.) meaning sacrifice is on it, then all base runners shall advance one base.

As previously stated there are no men or runners or checkers or the like used, to move over the surface of the game board, therefore in the balance of the description runners are referred to. This does not mean that runners are actually used over the surface of the board, but simply supposedly.

Caught off of any base.

35 Meaning the pitcher or catcher has thrown the ball to a baseman and he has touched the runner out before he could get back on the base.

Stolen bases.

40 Stealing any base means that the base runner has advanced a base without the aid of an error, sacrifice, or base hit. If there is a runner on third base, and a runner on first base, if the ball stops on the play, (stolen base) advance the runner on first base to second base. Never advance the runner on third base to home on the play (stolen base) if there is a runner on first base. If there is 45 a runner on second and a runner on third base you would have to advance the runner on third base to home scoring him. Never 50 advance both runners.

Out stealing any base.

55 Meaning the runner tried to advance a base without the aid of an error, sacrifice, or base hit, but was thrown out.

Out pitcher to first base.

60 Or "out third to first base," short to first base, second to first base, or "out at first base," ground ball, meaning the batter has knocked a ground ball to the first named 65 player who has fielded the ball and thrown

the runner out at first base. (Out at first base ground ball) meaning the batter has knocked a ground ball to the first baseman which he has fielded and touched first base before the runner could get to first base. 70 On all of these plays all base runners on bases shall advance one base except from third to home. When there are runners on all of the bases and with no outs or one out, and a ground ball is knocked to the pitcher, 75 short stop, or any baseman, instead of throwing the ball to first base as the play reads, use the play "out pitcher to home," "out third to home," "out second to home," etc., 80 cutting the opposing runner off at home. This lets the batter reach first base, other base runners advance one base.

Bunt out. (SAC)

85 Meaning the batter has tapped the ball to one of the in-fielders, such as pitcher, third baseman, short stop, etc., or towards first base or just in front of home base but the opposing player has fielded the ball throwing the runner out at first base. Advance 90 all base runners one base. The batter is out.

Bunt safe.

95 Meaning the batter has tapped the ball to one of the in-fielders, who could not field the ball in time to throw the runner out at first base. All base runners advance one base.

Foul out.

100 Meaning the batter has knocked the ball in the air not on fair territory that is caught by an opposing player. The batter is out. No base runner shall be allowed to advance.

Wild pitch.

105 Meaning the pitcher has thrown wild to the catcher which allows all base runners to advance one base. The batter does not take first base, in this game.

Passed balls.

110 Meaning a ball thrown by the pitcher that the catcher does not stop or catch. This allows all base runners to advance one base. The batter does not take first base in this game.

Balk.

115 Any motion by the pitcher while in position to deliver the ball to the bat without delivering it, or to throw to first base when occupied by a base runner, without completing the throw is called a balk. (There are more rules on balking in the official rule book 120 Spalding or Reach, but this will show enough so you can understand what is meant by a balk). All base runners advance one base. The batter does not take first base in 125 this game.

Ball four.

Meaning the pitcher has thrown four balls either too high, low or wide to become a strike. This entitles the batter to first base. If first base be occupied by base runner advance the runner on first to second. If first and second base be occupied by base runners advance both runners one base. If only second or third base be occupied by a runner don't advance the runner already on the base.

Hit by pitcher.

Meaning the pitcher has accidental hit the batter with a pitched ball. This entitles the batter to first base. Advance the runner on first base, etc., the same as ball four.

Man nearest home "out" hit by batted ball.

Meaning the batter hits a ball this ball hitting a base runner. The runner is out the batter goes to first base.

Intentional pass.

If the man at bat has been hitting the pitcher pretty regular, the pitcher sometimes gives the batter four balls in order to get to pitch to a weaker batter providing the bases are not full. In this game the intentional pass can be used at will by telling the scorer to put this batter on first base. The next man in order goes to bat.

Out first to pitcher at first base.

Meaning the batter has hit a ground ball towards first base. The first baseman going after the ball the pitcher covers first base. First baseman throws the ball to the pitcher putting the batter out before he can reach first base. All base runners advance one base in this game.

Out first to second at first base.

Meaning the same as out first to pitcher at first base with this difference. The second baseman covers first base instead of the pitcher.

Out second to home.

In order to make this play there must be a runner on third base. The batter hits a ball to the second baseman. The second baseman throwing the ball to the catcher. The catcher tags the runner from third base out at home. The batter reaches first base other base runners advance one base.

Out catcher to short to home.

To make this play there must be a runner on third base and either a runner on first or second base. If the runners are on second and third base, etc., the runner on second base pretends he is going to third base trying to get the catcher to throw to second base catching him off of second base and letting

the runner from third base score but instead of the catcher throwing to second base he only throws to the short stop who immediately returns the throw to the catcher catching the runner from third base out at home. If the runners are on first and third base the runner on first base pretends to steal second base the result is the same as above stated.

Double plays.

Out short to second to first. In order to make this play there must be a runner on first base. The batter hits a ground ball to the short stop who throws the runner from first out at second base. The second baseman throws the batter out at first base. If the bases are full use the play "out short to home" meaning the runner on third base is thrown out at home by the short stop. In cases where the play is used "out short to home" the batter reaches first base. If there is a runner on second base advance him to third base on either of these plays. If there is not a runner on first base do not use this play at all. (See impossible plays.) A double play cannot be made if there are more than one out.

Fly out to left field then throws runner from third out at home.

In order to make this play there must be a runner on third base. The batter hits a fly ball to left field the fielder catches the ball. The runner on third base tries to score but is thrown out at home by the fielder. All other base runners advance one base. If there are two outs use this play "fly out to left field".

Out pitcher to third to first.

In order to make this play there must be a runner on second base and not more than one out. This play can also be made if there are runners on both first and second base. The batter hits a ground ball to the pitcher the pitcher throws the ball to third base catching the runner from second out at third base. The third baseman throws the batter out at first. If there are runners on both first and second base advance the runner on first to second base. If there are two outs and a runner on second base use the play "out pitcher to third base". If there is no runner on second base do not try to use this play. (See impossible plays.)

Out second to short at second base.

In order to make this play there must be a runner on first base. The batter knocks a ground ball to the second baseman. The runner on first base starts for second base. The second baseman fields the ball and throws it to the short stop who covers second base putting the runner from first base out. This is called a force out. The batter

reaches first base. If there is a runner on second base, advance him to third base. If the runner is third don't use this play unless there are two outs.

5   *Changing pitchers.*

A pitcher may be taken out, (changed for another pitcher) any time in this game by telling the umpire. For an example; say, 10 you are pitching left handed and want to change pitchers for a right handed pitcher. Tell the umpire and merely change and pitch right handed. Never let another man pitch in your place as this would be a new team 15 taking your team's place.

In order to make it clear as to the manner of playing the game, the player pitches or tosses the members representing balls, on the board, and if two of the members roll off and 20 one stops on the play "out short to first base," count the member that stops on the play. In other words indicate the following symbol S to 1 on the score card, which symbol means "out short to first base."

25   Now take all three of the members as before and pitch one at a time, and if one rolls off, notice which was the first one on the board, that stopped on a play. For instance if one stops on the play "error third base" 30 put the symbol and abbreviation designating this point on the score card. Say the other one stops on the play "steal second base," advance the supposed runner to second base using the abbreviation and symbol designating the same.

35   Take all three of the members representing the balls and pitch over as before, and should the first one stop on "out strike 3" use the abbreviation and symbol. Should

the next member representing the ball stop 40 on "bunted out" use "catcher to first base sacrifice."

This would end the pitcher's half inning. The player sits down and his umpire and 45 scorer, while the opposing player (supposed to be the baseball team's pitcher) is pitching. This player or pitcher then pitches until three outs are made, and this is called the second player's half inning.

The invention having been set forth, what 50 is claimed is:

In a game apparatus, a game board provided with a baseball diamond thereon including a home plate, foul lines extending from the home plate, a fence connecting the terminals of the foul lines, thereby fencing off the outfield, baseball representations including baseball symbols applied upon the face of the diamond and over the outfield, the fence and beyond the fence, thereby indicating advantages and disadvantages, and a chart of symbols corresponding to the advantage and disadvantage symbols on the board, and a plurality of members having baseball representations thereon adapted to 65 be tossed upon the game board, for cooperation with the symbols on the game board, in combination with a score card ruled with intersecting lines to define columns for the 70 numbers of players and columns for the different innings, each column consisting of a plurality of spaces within which may be inscribed the indicia corresponding to the results obtained by registration of the playing members with the symbols on the board.

75   In testimony whereof I hereunto affix my signature.

JAMES D. TAGGART.
